UNITED STATES PATENT OFFICE.

HENRY P. CLAUSEN, OF ROCHESTER, NEW YORK, ASSIGNEE, BY MESNE ASSIGNMENTS,
TO WESTERN ELECTRIC COMPANY, OF CHICAGO, ILLINOIS, A CORPORATION OF
ILLINOIS.

TELEPHONY.

1,133,264.

Specification of Letters Patent. Patented Mar. 30, 1915.

Application filed January 12, 1912. Serial No. 670,771.

To all whom it may concern:

Be it known that I, HENRY P. CLAUSEN, a citizen of the United States, and resident of Rochester, county of Monroe, State of New York, have invented certain new and useful Improvements in Telephony, of which the following is a specification.

My invention relates to an improvement in the art of establishing telephone connections between subscribers, and to the switchboard, apparatus and circuits for establishing such a connection.

The object of my invention is to distribute the calls or traffic among the various operators in an exchange substantially uniformly. Various methods have been suggested for accomplishing this result, by means of an intermediate distributing frame, and later by means of automatic distributing switches. My present invention, however, accomplishes the result in a more uniform and less expensive manner, and without the aid of automatic distributing switches.

25 Tersely stated, my invention consists of a multiple switchboard in which a line signal for each line is given a definite position in one division of the switchboard and the various multiple jacks for this line are given 30 similar positions in other divisions of the switchboard.

An operator, whom I will term a "call operator," is located before the signal division of the switchboard, and other operators, whom I will term "connecting operators," are located before the various multiple jack divisions of the switchboard. The removal of the receiver at a subscriber's station displays a lamp in the signal division 40 of the switchboard. The call operator, who is provided with a transmitter and means to connect the transmitter with various connecting operators' receivers, observes the position and, therefore, the number of the signal displayed, and speaks this number into her transmitter, thus informing one of the connecting operators that the subscriber known by this number desires a connection. The connecting operator then inserts her 45 answering plug into the multiple jack of the line designated by the call operator and inquires for the desired number in the usual way. Having received the desired number, the connecting operator inserts her calling

55 plug into the multiple jack of the desired line and thus completes the connection. The call operator now connects her transmitter with another connecting operator and, as soon as another signal appears in the signal 60 section, speaks the number of this calling line into her transmitter and thus conveys it orally and telephonically to a second connecting operator who completes the connection as before described.

It has been found in practice that a call 65 operator can observe and call substantially 2400 calls per hour; it has also been observed, from practice, that an answering operator can readily complete 300 connections per hour, from which it will be seen 70 that one call operator would suffice for eight connecting operators. In this manner the number of connections completed by a single operator could be increased from 200 to 300 per hour, and the total number of operators 75 for the exchange could be reduced to two-thirds the number required for a multiple exchange in which each connecting operator supervises a definite group of 100 to 150 lines. To this must be added the required 80 number of call operators.

Other features and advantages of my invention will be pointed out in the following specification and claims.

My invention is illustrated in the accompanying drawings, in which—

Figure 1 illustrates three telephone lines with their signal lamps located in one division of the switchboard and with their multiple jacks located in corresponding positions in other divisions of the switchboard. Fig. 2 illustrates one method by which the call operator may be connected with the various connecting operators. Fig. 3 illustrates a modification embodying another method by which the call operator may be connected with the various connecting operators, and Fig. 4 illustrates a third modification by which the call operator may be connected with the various connecting operators. It is to be understood that other modifications may be made without departing from the spirit or scope of my invention.

In Fig. 1, each of the subscribers' stations 5, 6 and 7 is provided with a condenser 8 and annunciator 9 in a bridge between the line conductors 10 and 11, and with a transmitter 12 and receiver 13 in a bridge main-

tained normally open by contacts of the switch-hook 14. At the central office, line conductor 10 is connected through the contacts 15 and 16 of cut-off relay 17 and the 5 coil of line relay 18 with the live pole of battery A, and line conductor 11 is connected through contacts 19 and 20 of cut-off relay 17, with earth. Line conductor 11 is also connected through conductor 22 with the tip 10 contacts 23 of the multiple jacks, and line conductor 10 is also connected through conductor 24 to the ring contacts 25 of the multiple jacks. The sleeve contacts 26 of the multiple jacks are connected through conductor 27 and coil of cut-off relay 17, with earth. Line relay 18 controls normally open 15 contacts 30 and 31 in the circuit of the lamp signal 32. These lines are not provided with answering jacks of the character usually 20 denoted by that term, and the lamps for these lines are located in a division of the switchboard which contains no jacks of any character. This division is, for convenience, shown at one end of the multiple 25 switchboard, though it is to be understood that it may be upon any convenient position and need not even be in the same room or same exchange with the multiple jacks through which the conversational connection 30 is completed. It is to be understood that this circuit arrangement is typical and that any of the well-known multiple switchboard circuits may be substituted for the one here shown. A cord circuit for inter- 35 connecting these lines is illustrated with its answering and calling plugs located in their respective positions in the plug shelf of the multiple switchboard. This cord circuit, which is typical of the many which 40 would be used in an exchange of this type, is provided with the tip answering terminal 35, connected through conductor 36, condenser 37, conductor 38, contacts 39 and 40 of the operator's ringing key, and conductor 45 41, with the tip contact 42 of the calling plug. The sleeve contact 44 of the answering plug is connected through conductor 45, condenser 46, conductor 47, contacts 48 and 49 of the operator's ringing key, and conductor 50, with the sleeve contact 51 of the calling plug. The tip and sleeve answering 55 supervisory relays 53 and 54 and the main battery A are connected in a bridge between the talking strands 36 and 45 of the cord circuit. These relays co-operate to control the answering cord supervisory signal 55 in a manner well known in the art. The calling supervisory relays 56 and 57 are similarly connected and similarly control the 60 circuit of the calling supervisory signal 58.

Referring to Fig. 2, the call operator located before the signal division is provided with the transmitter 55 and key 56. Associated with these is the step-by-step 65 switching mechanism 57. The conductors

58 and 59, leading from the secondary of the operator's induction coil 60, are connected with the segments 61 and 62 of the switch 57, the brushes 63 and 64 being adapted to connect these segments with the various contacts 65 and 66, arranged about the circumference of the switch. Contacts 65 and 66 are arranged in pairs, each associated pair being located 120 degrees apart in the circumference of the switch, and these contacts being connected with one of the operators' receivers 68, which is located at a connecting operator's position. The switch is provided with a third segment 70 and brush 71 connecting this segment with the 70 various contacts 72, these contacts being connected through conductors with the various lamps 74 located at the various connecting operators' positions. A particular contact 72 is connected with a lamp located 75 in a position, one in advance of the position to which the two contacts, which are 120 degrees from the particular contact 72, are extended. Segment 70 is connected with the live pole of a battery and the lamps at the 80 various operators' positions are grounded so that when the call operator's circuit is connected with the first connecting operator's receiver, the lamp at the second connecting operator's position is displayed, 85 thus indicating to the second operator that she will receive the next connection with the call operator. The key 56 is connected through the motor-magnet 76 so that the depression of the key completes the circuit of 90 the motor-magnet and steps the switch, one step at a time, in a clock-wise direction.

In Fig. 3 I have shown a modification by means of which the transmitter 78, located at the call operator's division, may be connected to any one of the receivers 79 by the selective operation of the push buttons 80.

In Fig. 4 I have shown a further modification, the transmitter and receiver circuits of which operate the same as described in connection with Fig. 2, but in which each of the connecting operators is provided with a barring key 82, each of which normally grounds a contact 83 of the rotary switch 84. The normal operating circuit for the 110 motor-magnet 85 is, therefore, from the live pole of battery A, through the contacts of the call operator's switch 86, conductor 87, coil of motor-magnet 85, segment 88, brush 89, and the various contacts 83 and switches 115 82, to ground. If, for some reason, an operator is unable to complete a connection, or wishes to leave her position, she may throw her key 82 to its alternative position, in which case an interrupted ground will be substituted for the permanent ground. When the brush 89 comes upon this contact of the rotary switch 84, by reason of the actuation of the call operator's key 86, instead of the switch 81 taking one step, it will take two 120 125 130

steps by reason of the rotation of the interrupter 90 and the consequent interruption of the circuit through the motor-magnet 85.

In the operation of my system a subscriber

- 6 removes the receiver 13 from the switch-book at the sub-station and thus completes the circuit of the line relay 18 and displays the associated line lamp 32 located in the call operator's division of the switchboard.
- 10 The call operator, observing the display of this signal and observing its location in the switchboard, speaks the number of the associated line into her transmitter, this being heard by one of the connecting operators.
- 15 The connecting operator receiving this number lifts her answering cord plug and inserts it into the multiple jack designated by the call operator. The connecting operator then obtains the desired number and tests 20 the jack of the desired line to learn its busy or idle condition and, if idle, inserts the calling plug into the jack and rings in the usual manner. The supervision of the connected lines is now controlled by the connecting operator by means of her supervisory lamps 55 and 58 and the plugs are removed from the jacks upon the display of these lamps. Immediately after giving the 25 number of the calling line to the connecting operator, the call operator presses her button 86 (Fig. 2), or one of the buttons 89 (Fig. 3), or the button 86 (Fig. 4), as the case may be, and connects herself with the next connecting operator and speaks the 30 number of the next calling line, the connection being completed by this operator. The same is previously described.

It is to be understood that several call operators may be located in front of the call operator's position. There is no necessity for the call operators to sit close to the switchboard and they, therefore, may be grouped in any convenient manner about the call operator's division so that there will be 40 no interference, even though as many as eight or ten call operators are used. Each call operator may be given a vertical or horizontal section of the lamps, and these sections may be increased or diminished in size, 45 according to the time of day and the amount of traffic, so that each call operator may at all times handle from 150 to 200 calls per hour. The number of connecting operators associated with each call operator may be varied, according to the ability of the operators; that is, it may be found that in one group five connecting operators could handle all the calls from one call operator, whereas in another group eight, and in still 50 another group ten, connecting operators would be required to complete all of the connections indicated by the call operator for that particular group.

It is to be understood that while I have 55 here shown and described a preferred em-

bodiment of my invention, I do not wish to be unduly limited thereto, many modifications being possible without departing from the spirit or scope of the invention.

I claim—

1. In a telephone system, the combination with a plurality of telephone lines, of a lamp for each line and a plurality of multiple jacks for each line, all of said lamps being located before certain operators and all of the jacks being located before different operators at the central office, and means of communication between the operator before the lamps and the operators before the jacks, whereby the display of any lamp may 70 be communicated to the operators located before the jacks, and means controlled solely by the operators before the jacks for establishing connections between calling and desired lines.

2. In a telephone system, the combination with a telephone line, of a line signal therefor at a call operator's division free from talking conductors of said line, and multiple jacks therefor at connecting operators' divisions, means to telephonically communicate the number of the calling line from the signal division to the connecting divisions, and means at the connecting operators' divisions only for establishing connections 90 with said line as a calling or a called line.

3. A telephone switchboard having one division containing only line signals, one for each line, other divisions containing only multiple jacks, one for each line in each division, said divisions being in charge of different operators, means in said switchboard by which the operator in charge of the signal division may disclose to the operator in charge of any one of the jack divisions the identity of any displayed signal, and interconnecting means for the lines out of control of the operators at the signal division.

4. A telephone switchboard comprising a plurality of divisions, line lamp signals located in one of said divisions, multiple jacks corresponding to said line lamp signals located in all of the other of said divisions, and means for telephonically communicating the identity of a displayed line lamp signal 110 from an operator in position to observe the signal division to an operator in position to connect with a multiple division of the switchboard without the signal operator making any connection with said line, and 115 interconnecting means for connection between two multiple jacks of the same division.

5. In a telephone system, the combination with a call operator's division and a plurality of connecting operators' positions, of interconnecting circuits at the latter positions, a step-by-step switch, a key at the call operator's position for actuating said switch, a transmitter at the call operator's position, 120

- and a receiver at each of said connecting operators' positions independent of the interconnecting circuits, and circuit connections whereby the call operator's transmitter 5 is connected to the various connecting operators' receivers one at a time and in sequence through the contacts of said switch whereby the call operator may communicate with the connecting operators, one at a time.
- 10 6. The method of interconnecting telephone lines, consisting in displaying a signal for a calling line to one person at the central office, transmitting the identity of the calling line orally to another person at 15 another division at the central office, connecting directly with the calling line at the latter division in response to said oral instructions, receiving the number of the desired line directly from the calling subscriber 20 at the latter division of the switchboard and completing thereat a connection between the calling and desired telephone lines.
7. In a telephone system in combination,
- a calling operator's division of the switchboard, and a plurality of connecting operators' divisions, circuits extending between the calling operator's division and each of said connecting operators' divisions, a transmitter at the calling operator's division and a receiver and lamp at each of the connecting operators' divisions, means whereby the calling operator may connect her transmitter with the receivers at the connecting operators' positions in a given order, and means for displaying the lamp at the connecting 35 operator's position with which the calling operator's transmitter will be next connected in the given order.
- Signed by me at Rochester, county of Monroe, and State of New York, in the 40 presence of two witnesses.

HENRY P. CLAUSEN.
